DRILLING PROCEDURE AND APPARATUS

Ben W. Sewell, Tulsa, Okla., assignor to Standard Oil Development Company, a corporation of Delaware

Application March 19, 1948, Serial No. 15,845

1 Claim. (Cl. 255—21)

1

The present invention is directed to drilling apparatus. In particular the invention relates to a novel chain cutter adapted to cut boreholes in the earth.

The art of drilling boreholes into the earth has been very well developed. The conventional method now employed for drilling deep holes is the so-called rotary method in which there is employed a mud flush passing down through the center of a drill stem which supports and turns a cutting head. The mud is ejected from the drill stem adjacent to the cutting head and then passes up the outside of the drill stem, performing various functions to facilitate the drilling. In the art of exploration for oil, there are a great many procedures which require the drilling of boreholes, such as the seismic method in which shot points up to two or three hundred feet may be drilled; the thermal method in which drill holes up to fifty feet are necessary for the location of thermometers; sampling methods in which it is desired to take the samples below the level of the uppermost water table, thereby necessitating drill holes of twenty feet or greater; the coring method in which drill holes ranging from two hundred to about a thousand feet are employed; and the like. It is quite commonly the case that these exploration procedures are performed in wild undeveloped country where there are dense forest growths and thick brush, or in extremely arid regions. In either of these cases any drilling method which requires the use of water, drilling fluid, or mud necessitates the transportation of the necessary fluid to the location of each drill hole and as indicated, in certain areas this may be practically impossible.

In various types of mining also it is desirable to have a drilling method by means of which relatively shallow holes can be drilled rapidly and cheaply.

The principal object of this invention is the provision of an apparatus for drilling earth boreholes, in which the drilling operation may, if desired, be carried out without the employment of drilling fluid.

An additional object of the present invention is the provision of a drilling apparatus which will drill a hole of a selected configuration and which greatly diminishes the danger of the hole deviating from the vertical.

Other objects and advantages of the present invention will appear in the following detailed description of the accompanying drawings in which:

2

Figure 1 is a front elevation of one form of apparatus according to the present invention and;

Figure 2 is a side elevation of the chain cutter of the present invention in operative position and;

Figure 3 is a cross section view along the line 3—3 of Figure 2 and;

Figure 4 is a transverse section along the line 4—4 of Figure 1 and;

Figure 5 is a vertical transverse section along the line 5—5 of Figure 4 and;

Figure 6 is a partial vertical section along line 6—6 of Figure 2.

15 In essence, the apparatus of the present invention comprises an endless chain, the individual links of which constitute cutting surfaces, the chain being stretched over an elongated framework, carrying at either of its ends sprockets for driving the chain. The framework is provided with means for raising it and lowering it in a borehole and is so constructed as to permit the ready insertion of additional lengths into the framework. Similarly, additional links may 20 be added to the chain so that the entire assembly is adjustable in length. Combined with the framework is a driving mechanism for driving the sprockets and the chain while the assembly moves downwardly.

30 Referring to the drawings, numeral 1 designates a prime mover, the driven shaft of which enters and extends into a casing 2 in which it is coupled to a rotary table in the manner conventional in apparatus of this type. The rotary table has a shaft which extends upwardly in the form of a post 3, this post having for most of its length a non-circular cross section. Suspended from a suitable derrick by a cable 4 is the cutting chain assembly 5 which is disposed 35 parallel to the post 3. The cable 4 has affixed to its lower end a U-shaped bracket 6, in which is journaled the shaft 7 of a sprocket wheel 8. The chain 5 rides on the sprocket wheel and is composed of individual links pivoted to each other, each link being a bucket-like member having a sharpened leading edge or lip in the direction of travel of the chain.

40 The chain is held and stretched in position by an interior framework 9 made up of structural members 10. The uppermost structural member terminates at its upper end in a U-shaped bracket 11, the free ends of which brace the shaft 7. The lowermost structural member terminates at its lower end in a similar U-shaped bracket 13 between 45 the free ends of which is journaled another

sprocket wheel 14 over which the chain is engaged. The abutting ends of the structural members 10 have flat faces and are bolted together so that similar members having both ends flattened may be interposed between the end structural members. In this way the framework can be made as long as desired simply by adding additional members. It will be understood of course that as each new section of framework is added there must be a corresponding addition of links to the chain.

Connected to the U-shaped bracket 6 by a suitable brace 15 is a gear box 16 which has clearance openings in its top and bottom walls so as to accommodate the post 3. The shaft 7 of the upper sprocket wheel extends into the gear box 16 and terminates therein in a bevel gear 17. Engaged with this gear is a horizontally disposed bevel gear 18, having as its center a bushing 19 with a central opening corresponding in configuration to the periphery of the post 3. Beneath this gear is a horizontal plate 20 bolted to the side wall of the gear box. Between the plate 20 and the gear 18 is a coil spring 21 which serves to keep the horizontal gear 18 constantly in mesh with the bevel gear 17.

At the start of the drilling operation, the entire assembly is in the position shown in Figure 1 with the gear box near the top of the rotating post 3. By suitably adjusting the tension in cable 4, an operator can impose as much as the full weight of the chain assembly as desired on the earth. A prime mover 1 is then set in operation and through the rotary table 2, rotates the post 3 which in turn drives the upper sprocket wheel 8 and the chain 5. The bucket-like cutting links of this chain cut and remove earth as the operation proceeds. As the drilling progresses, the gear box 16 slides downwardly along the post 3 until such time as it becomes necessary to add additional structural members in the chain support and links to the chain. By the nature of this apparatus, cutting generally occurs in a substantially vertical direction. However, any tendency for the chain cutter to depart from the vertical can immediately be noted and compensated for by applying a horizontal force against the support 9 of the cutter. This may be accomplished, for example, simply by holding a bar against one of the structural members 10. Once the hole has been started there will be practically

no tendency for cutting in a lateral direction since the weight of the chain, the supporting framework and the gear box will drive the mechanism downwardly. Application of the 5 horizontal force will ordinarily not be necessary if the hole is started by digging a small pit which is frequent practice when drilling boreholes in the earth.

Having now fully described the present invention, 10 what is claimed and desired to be protected by Letters Patent is:

An apparatus for cutting holes in the earth comprising an elongated vertical framework, said framework being constructed in separable sections and adapted to be lengthened by the insertion of additional similar sections, upper and lower sprockets having axles attached to the top and bottom ends respectively of said elongated framework, an endless chain stretched over said 15 framework and engaged with each of said sprockets, and adapted to be lengthened, bucket-like links attached at evenly spaced intervals along said chain, said links having sharpened edges, a bracket supporting the axle of said upper 20 sprocket and adapted to be suspended from a supporting cable, a gear box attached to said bracket, a bevel gear attached to the axle of said upper sprocket and vertically disposed within said gear box, a second bevel gear horizontally 25 disposed within said gear box in meshed relation with said first bevel gear, said second bevel gear being provided with a central non-circular opening, a vertical shaft having a non-circular cross section corresponding substantially in shape to 30 said non-circular opening, said shaft being slidably engaged with said second bevel gear, and means for rotating said shaft.
